(57) **CLAIM**

The ornamental design for a clip for heat sink, as shown and described.

DESCRIPTION

FIG. 1 is an isometric view of a clip for heat sink showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an isometric view thereof in an alternate position of use; and,

FIG. 9 is an isometric view thereof showing the clip for heat sink being used to mount a heat sink to a retention module, wherein the heat sink and the retention module are shown in broken lines for illustrative purpose only and form no part of the claimed design.
